(74) Attorney, Agent, or Firm — MLO, a professional corp.

(57) **CLAIM**

The ornamental design for a lighting fixture, as shown and described.

DESCRIPTION

FIG. 1 is a perspective view of a lighting fixture, showing our new design;

FIG. 2 is a front view of the lighting fixture;

FIG. 3 is a rear view of the lighting fixture;

FIG. 4 is a right view of the lighting fixture;

FIG. 5 is a left view of the lighting fixture;

FIG. 6 is a top view of the lighting fixture; and,

FIG. 7 is a bottom view of the lighting fixture.

The broken lines in the drawings illustrate portions of the lighting fixture which form no part of the claimed design.
